CLAIM

We claim the ornamental design for a reticle for a gunsight or other projectile weapon aiming device, as shown and described.

DESCRIPTION

FIG. 1 is a front elevational view of a reticle for a gunsight or other projectile weapon aiming device in accordance with our new design; and,

FIG. 2 is a perspective view showing an environment of use for the reticle of FIG. 1.

In the figures, the broken lines indicate environmental features that form no part of the claimed design.
